BADGE.

No. 20,159.

Patented Sept. 23, 1890.

UNITED STATES PATENT OFFICE.

NATHAN S. BOYNTON, OF PORT HURON, MICHIGAN; ASSIGNOR TO BOYNTON & SON, OF SAME PLACE.

DESIGN FOR A BADGE.

SPECIFICATION forming part of Design No. 20,159, dated September 23, 1890.

Application filed August 7, 1890. Serial No. 361,396. Term of patent 7 years.

To all whom it may concern:

Be it known that I, NATHAN S. BOYNTON, a citizen of the United States, residing at Port Huron, in the county of St. Clair and State of Michigan, have invented and produced a new and original Design for Badges, of which the following is a specification, reference being had to the accompanying drawing, forming a part thereof.

10 The object of the invention is a badge consisting of a circular medal suspended from a pin-bar as a pendant to give it a pleasing and unique appearance, and the invention consists in the peculiar configuration and design 15 of the various parts, all as more fully hereinafter described.

The design consists of a circular medal having an annular margin and an inner circular field contrasted therewith, with suitable 20 inscriptions thereon, and with rays radiating from the point of suspension.

The lower cross-bar is of a substantially

rectangular shape, with an ornamental border formed within a plain panel with an elevated cross-bar thereon, having its lower 25 edge arched concentrically with the top of the medal. Above this cross-bar is the pin-bar, of elongated diamond shape, having an ornamental border forming within a panel of corresponding outline, and the two bars being connected by a ribbon or a representation 30 of a ribbon with vertical bars of color.

Suitable inscriptions and representations may be placed upon the panels and upon the annular and circular field of the medal. 35

What I claim as my invention is—

A design for a badge, substantially as herein shown and described.

In testimony whereof I affix my signature in presence of two witnesses.

NATHAN S. BOYNTON.
